UNITED STATES PATENT OFFICE

2,504,808

METHOD OF ANNEALING

William H. Dailey, Jr., Library, Pa., assignor to
Carnegie-Illinois Steel Corporation, a corpora-
tion of New Jersey

Application June 2, 1945, Serial No. 597,323

1 Claim. (Cl. 148—16.7)

1

The present invention relates to an improved method of annealing which, while not limited thereto, is well suited for annealing relatively wide coils of rolled steel strip.

It is well known to those skilled in the art that heretofore the annealing of coiled steel strip has been frequently carried out by enclosing the coils within bell-like gas-tight inner covers whose lower edges are sealed in sand or other suitable sealing material, the annealing heat having been applied externally by a bell-type radiant tube annealing furnace. In such conventional practice a protective deoxidizing gas is introduced into the inner covers so as to force out air and maintain a deoxidizing atmosphere within the inside cover. The gas forming the non-oxidizing atmosphere is usually exhausted through the sand seal at the base of the inner cover or through suitable outlets, the rate of flow of the deoxidizing gas being controlled by maintaining a uniform gas pressure inside the inner covers or by maintaining a uniform gas pressure in the non-oxidizing gas supply by manipulation of an adjustable pressure-regulating valve.

The above described conventional method of distributing deoxidizing gas to the inner covers is inefficient and objectionable for the reason that the flow of gas through the inner covers decreases as the temperature inside the cover increases, and said gas flow, on the other hand, increases when the temperature inside the cover decreases. My invention is based on the recognition of the fact that contaminating gases are evolved from oil and water accretions on the surfaces of the steel coils during the heating period which should be purged from the inner covers by the maximum rate of flow of deoxidizing gas during this heating stage of the annealing treatment, but that after the heating stage, that is to say, during the cooling period after the application of heat to the furnace has been discontinued, the purging action is no longer necessary and the rate of flow of the deoxidizing gas can be reduced to the minimum necessary to prevent outside air from entering the inner cover, thus effecting a great saving in deoxidizing gas consumption.

One object of the present invention is to provide a method of involving controlling the flow of gas to the inner covers at a substantially constant rate regardless of pressure variations inside the inner covers or pressure variations of gas emanating from the inlet pipes.

Another object of the invention is to provide a method of maintaining the rate of flow of

deoxidizing gas at the maximum necessary to obtain the desired purging action during the heating stage and for maintaining the rate of flow of deoxidizing gas during the cooling stage, at the minimum necessary to prevent entrance of air into the inner covers.

The invention will be more fully apparent from consideration of the following specification, the accompanying drawings, and the appended claims.

In the drawings:

Figure 1 is a somewhat diagrammatic plan view of a novel combination of annealing apparatus suitable for carrying out the herein claimed method.

Figure 2 is a cross-sectional view on line II—II of Figure 1.

Referring more particularly to the drawings, reference numerals 10 and 12 represent suitable frame members secured to a plate 14 on which is mounted a refractory base 16. Retained between the members 10 and 12 is a body of sand, indicated at 18, forming a gas seal. An outer annealing furnace hood 20 is seated at the bottom of this sand seal. This furnace may be of any conventional form such as the well known type having radiant heater tubes. The refractory base 16 is formed with a plurality of raised platforms 22 each adapted to accommodate a stack of coiled material such as the coils C of strip steel indicated in the drawings.

Each stack of coils C is adapted to be enclosed by an inner bell-like cover 24 of generally circular form, closed at the top, the bottom of the cover resting in a body of sand or other sealing material such as indicated at 26, the base being provided with suitable raised portions 28 to retain the sand or other sealing material.

The apparatus thus far described in detail is of somewhat conventional and well known form. But although the apparatus and its chief components parts, broadly speaking, are old per se and well known to those skilled in the art, they are combined and operated in a novel manner so as to give rise to materially improved operating results. The novelty of the method as more fully elaborated hereinafter resides chiefly in supplying a non-oxidizing gas inside the covers 24 at a substantially constant, relatively high rate during the heating stage, and at a uniform pressure substantially higher than the maximum pressure to be encountered under the inner cover, and during the cooling stage to supply the deoxidizing gas at a materially lower yet still constant rate and uniform pressure. As shown in

the drawings, 30 represents a source of deoxidizing gas which is connected by a supply pipe 32 having a control valve 34 and a flow indicator 36 therein which is adapted to deliver a deoxidizing gas at a uniform pressure and substantially constant rate to a gas header 38 extending lengthwise below the base 16. A plurality of branch pipes 40 lead from the main 38, and each branch pipe contains a fitting 42 having an orifice O therein of predetermined diameter, and between each fitting 42 and the main each branch carries a shut-off valve 44.

The main control valve 34 is adapted to be manually manipulated to regulate the gas flow, and the gas passes through the flow indicator 36 which has an orifice of predetermined size and is equipped with conventional means for indicating the rate of gas flow. The orifices in the fittings 42 of the branch pipes are so designed that they provide sufficient pressure drop to give substantially uniform distribution of deoxidizing gas under all conditions.

By using the apparatus and distributing system illustrated, the rate of gas flow is shown at all times by means of the rate-of-flow indicator 36, and this rate of flow can be set at the will of the operator at any desired value by manipulation of the control valve 34. It is thus apparent that during the heating period of the annealing treatment, a substantially constant amount of gas per unit of time can be delivered to each of the inner covers 24. By way of example, during this period when heat is being applied by the radiant heat supplied by the annealing furnace bell 20, the operator may so set the control valve 34 as to provide approximately 50 cubic feet of deoxidizing gas per hour to the interior of each inner cover 24. This amount, of course, will vary with the tonnage of steel being treated, and in this example it is assumed that approximately 15 tons of steel strip are contained within each inner cover 24. And during the cooling period, after the outer cover 20 has been removed and the radiant heat is no longer being applied to the coils C, the control valve 34 will be operated so as to supply a lower rate of input of deoxidizing gas, yet this input will be maintained substantially constant so as to adequately maintain a super-atmospheric pressure within the inner covers to thus exclude the entrance of air. During this cooling stage valve 34 may, for example, be set so as to admit approximately 20 cubic feet of non-oxidizing gas per hour, at a uniform pressure.

From the foregoing it is apparent that the layout of the deoxidizing gas distribution system is such that the branch lines 40 are equipped with orifices designed with sufficient pressure drop to provide substantially uniform distribution of deoxidizing gas under all conditions and that because of the inclusion of the flow indicator 36 and the control valve 34 the rate of gas flow is made known to the operator at all times. Such rate of flow can be set at any desired value by

manipulation of the control valve 34. Thus it is apparent that during the heating step, when gases are evolved from oil and water accretions on the surfaces of the coil C, resulting from normal steel rolling practice, a constant maximum supply of deoxidizing gas can be supplied at a uniform pressure so as to exert a purging action. Thereafter, during the cooling stage, upon cutting off of the heat by removal of the outer hood 20, the supply of deoxidizing gas will be reduced to the minimum necessary to prevent outside air from entering under the inner cover.

Since gas is being constantly supplied, namely, at a uniform high rate during the heating stage and at a uniform low rate during the cooling stage, during both stages the excess gas escapes or filters out through the sand seals 26 surrounding the inner covers 24. If desired, escape ports can be used. The equipment will usually include a conventional motor-driven fan 46 for circulating the gas within each inner cover 24.

Although an actual reduction to practice shows that the above described embodiment of the invention is highly desirable, it is not to be construed that I am limited thereto, since various modifications may be made by those skilled in the art within the scope of the appended claim.

I claim:

30 In the annealing of coils of rolled steel material carrying accretions of foreign matter such as oil and water resulting from normal steel rolling operations, the method which comprises enclosing the coils within a cover and heating them to a determined annealing temperature while delivering a substantially constant maximum supply of deoxidizing gas to said cover at a substantially uniform pressure which is substantially higher than the maximum pressure under the cover so as to purge the cover of contaminating gases evolved from said accretions, then cutting off the heat and allowing the coils to cool for a determined interval and upon cutting off the heat, reducing the supply of deoxidizing gas to the minimum necessary to prevent air from entering the cover.
